[57] **CLAIM**

The ornamental design for a portable satellite antenna mount, as shown and described.

DESCRIPTION

FIG. 1 is an environmental perspective view of a portable satellite antenna mount showing my new design;

FIG. 2 is a top view thereof;

FIG. 3 is a front elevational view thereof;

FIG. 4 is a left side elevational view;

FIG. 5 is a rear elevational view thereof; and,

FIG. 6 is a right side elevational view.

The undisclosed bottom is unornamented.

The broken line showing of the antenna and support pole is for illustrative purposes only and forms no part of the claimed design.
